UNITED STATES PATENT OFFICE.

ERIC HERMAN DELLING, OF STRATFORD, ONTARIO, CANADA, ASSIGNOR TO BROOKS STEAM MOTORS LIMITED, OF STRATFORD, CANADA.

FUEL-OIL BURNER.

Application filed September 3, 1926. Serial No. 133,415.

The principal objects of the invention are, to overcome the difficulties met with in the burning of oil fuel in the limited space afforded in boilers of the type used in steam motor cars, and to provide means for effectively eliminating the depositing of soot upon the tubes of the boiler, thereby obviating the necessity of frequent cleaning of the boiler and enhancing its use.

10 The principal feature of the invention consists in the novel construction and arrangement of a combustion chamber for a short length tubular boiler, whereby the air and finely atomized fuel mixture in its first 15 stages of combustion is divided and directed around a circular chamber arranged at the head of a central passage to direct the flame through the boiler flues.

In the accompanying drawings, Figure 1 20 is a vertical sectional view through a boiler showing the application of my invention thereto.

Figure 2 is a horizontal section on the line 2-2 of Figure 1.

25 In the use of liquid hydrocarbon fuels for heating small boilers, such as are used in motor cars, tractors and like machines, great care is experienced by the precipitation of carbon from unburnt fuel upon the tubes 30 which are comparatively cool.

In the present arrangement the boiler 1 which is of the vertical tubular type and has a large central passage 2 therethrough and the boiler is enclosed within a casing 3, 35 being spaced from the bottom and the outer walls thereof.

A deflector cone 4 is arranged centrally of the bottom of the casing 3 to deflect the gases of combustion flowing downwardly 40 through the central passage 2 outwardly with a smooth flow and free from eddy currents.

The casing 3 extends considerably above the top of the boiler and is preferably provided with a dome top 5.

Within the dome 5 and spaced from the walls thereof is a circular casing 6 having a slightly arched top 7 and a central tubular extension 8 extending downwardly from the bottom to enter the central passage 2 of the boiler.

The lower end 9 of the tubular extension 8 is preferably enlarged.

A radial tubular extension 10 is formed

on one side of the casing 6 and projects outwardly through the casing 3 and is connected with a suitable blower 11.

A fuel discharge nozzle 12 extends into the radial extension 10 of the casing 6 and directs a finely atomized spray of hydro- 60 carbon into the circular casing 6.

Directly opposite the inner end of the extension 10 is arranged a vertical portion 13 which is of V-shape having the apex thereof directed toward said extension and the flanges projecting inwardly.

This V-shaped partition being arranged directly in the path of the inflowing air and atomized oil divides the stream of the mixture, causing it to flow around the chamber in two uniform streams.

Suitable means for igniting the mixture is provided, a spark plug 14 being arranged close to the nozzle 12.

The burning mixture flows into the circular combustion chamber, being directed around the same by the partition 13 and the two streams of flame meeting opposite to the point of ingress and flowing downwardly through the tube 8.

The mixing of the combustible materials effected by the division and then flowing together of the flame ensures complete combustion of the mixture before the end of the tube 8 is reached so that no visible flame 85 shows at the lower end thereof. The hot gases produced by the combustion are then divided uniformly by the cone 4 and directed laterally under the bottom of the boiler to flow upwardly through the tubes and 90 around the outer side, passing over the top and flowing around the combustion chamber formed by the casing 6.

It will be seen that the maximum heating value of the fuel is obtained by the structure herein disclosed.

The present invention is shown and described as applied to the tubular boiler type but it must be understood that it may be applied to other forms of heat exchange apparatus, the invention being in the means for effecting the combustion of the fuel.

What I claim as my invention is:-

1. In a fuel oil burner, a combustion chamber having an inlet passage adapted to direct a combustible mixture thereto, a central passage opening from the bottom of said combustion chamber, and means dis-

posed between said passages for dividing the flow of mixture directing it around the walls of the combustion chamber.

2. In a fuel oil burner, a circular combustion chamber having a radial inlet, a diverging partition arranged opposite said inlet and dividing the inflowing combustible mixture and directing it around the inner wall of the combustion chamber, and a central 10 tubular outlet opening from the bottom of said combustion chamber immediately back of said diverging partition, said partition effecting an indirect communication between the inlet and outlet.
- 15 3. In a fuel oil burner, a circular casing having an arched top and an arched bottom, a tubular extension opening from the arched bottom and arranged axially, a V-shaped partition extending between the top and the

bottom to one side of and above the opening 20 to said extension and spaced from the side wall of said casing, and an inlet passage leading radially into said chamber opposite the apex of said V-shaped partition.

4. In a fuel oil burner, a circular casing 25 having a central tubular extension opening from the bottom thereof, said extension having an enlarged lower end, an inlet passage extending radially into said casing at a level higher than the opening to said tubular extension, a deflecting partition arranged opposite said inlet and spaced from the side wall of said circular chamber adapted to divide the inflowing combustible material and direct it around the inner periphery of 30 35 the combustion chamber.

ERIC HERMAN DELLING.
